Specification for Design.

Patented May 16, 1916.

Application filed March 20, 1915. Serial No. 15,975. Term of patent 14 years.

To all whom it may concern:

Be it known that we, ROBERT O. HENDRICKSON and CLARENCE M. EASON, citizens of the United States, residing at Cleveland, in the county of Cuyahoga and State of Ohio, and at Chicago, in the county of Cook and State of Illinois, have invented a new, original, and ornamental Design for Tractor-Bodies, of which the following is a specification, reference being had to the accompanying drawing, forming part thereof.

The figure is a perspective view of the tractor body showing our new design.

Copies of this patent may be obtained for five cents each, by addressing the "Commissioner of Patents, Washington, D. C."

We claim:

The ornamental design for a tractor body as shown.

ROBERT O. HENDRICKSON.
